[57] CLAIM

The ornamental design for a conduit hanger, as shown and described.

DESCRIPTION

FIG. 1 is a top left perspective view of the conduit hanger showing our new design;

FIG. 2 is a bottom left perspective view of the conduit hanger of FIG. 1;

FIG. 3 is a top plan view of the conduit hanger of FIG. 1;

FIG. 4 is a front elevational view of the conduit hanger of FIG. 3;

FIG. 5 is a bottom plan view of the conduit hanger of FIG. 3;

FIG. 6 is a side elevational view of the conduit hanger of FIG. 3;

FIG. 7 is a top left perspective view of an alternative embodiment of the conduit hanger showing our new design;

FIG. 8 is a bottom left perspective view of the conduit hanger of FIG. 7;

FIG. 9 is a top plan view of the conduit hanger of FIG. 7;

FIG. 10 is a front elevational view of the conduit hanger of FIG. 9;

FIG. 11 is a bottom plan view of the conduit hanger of FIG. 9; and,

FIG. 12 is a side elevational view of the conduit hanger of FIG. 9.

The broken line showing of a pipe is for illustrative purposes only and forms no part of the claimed design.
